US0D1049535S

(12) **United States Design Patent** (10) **Patent No.:** **US D1,049,535 S**
(45) **Date of Patent:** **** Oct. 29, 2024**

(54) **LEAF COLLECTOR**

(71) Applicant: **Shenzhen Aichong Industry Co., Ltd,**
Shenzhen (CN)

(72) Inventor: **Aicheng Yin, Changning (CN)**

(**) Term: **15 Years**

(21) Appl. No.: **29/947,587**

(22) Filed: **Jun. 17, 2024**

(51) **LOC (14) Cl. 09-09**

(52) **U.S. Cl.**

USPC **D34/1; D32/74**

(58) **Field of Classification Search**

(57) **CLAIM**

The ornamental design for a leaf collector as shown and described.

DESCRIPTION

FIG. 1 is a perspective view of a leaf collector showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof; and,

FIG. 8 is bottom plan view thereof.

The broken lines illustrate portions of the leaf collector that form no part of the claimed design.

The dash-dot and the dash-dot-dot broken lines shown in the figures depict portions of the leaf collector which form no part of the claimed design.

1 Claim, 8 Drawing Sheets
